UNITED STATES PATENT OFFICE

2,087,139

LIQUID SUPPLY NOZZLE

William P. Cameron, Philadelphia, Pa.

Application July 22, 1936, Serial No. 91,957

5 Claims. (CL. 221—80)

This invention relates primarily to attachments for liquid-supply nozzles of the type, for example, employed on distributing pumps of gasoline service stations.

5 The principal object of the invention is to provide an attachment for liquid-supply nozzles of the character set forth affording said nozzles distinctly improved anti-drip characteristics.

10 Another object of the invention is to provide an anti-drip device of the stated character that can be readily applied to the existing discharge nozzles.

15 A further object of the invention is to provide a device of the character set forth of resilient material having a substantially smooth surface which will function as a buffer and prevent scratching or marring of the paint or enamel finish on the body of an automobile or other surface.

20 These and other objects of the invention and the features and details of construction thereof are set forth hereinafter and shown in the accompanying drawing, in which:

25 Figure 1 is a view in side elevation of a nozzle including the anti-drip device, and

Fig. 2 is an enlarged fragmentary view in section on line 2—2, Fig. 1.

With reference to Figure 1 of the drawing, the nozzle therein illustrated, with the exception of the tip attachment hereinafter described, is of the conventional type comprising a hand-grip portion 1, a control valve 2 which is actuated in a well known manner through the medium of a lever 3, and a tubular discharge portion 4. In accordance with the usual practice, the portion 4 extends at an angle to the portion 1 to facilitate the manipulation thereof in supplying gasoline to the motor vehicle and also in some degree to aid in avoiding drip from the end of the nozzle when the latter is withdrawn from the tank of the motor vehicle. With a nozzle of this character, it is possible to avoid drip only at the expense of a considerable delay to permit all of the gasoline left in the outer portion 4 of the nozzle to escape after the valve 2 has been closed.

For the purpose of substantially eliminating drip, the present invention contemplates an auxiliary tip or attachment 5 provided with a suitably formed internal liquid-retaining recess 6 adjacent its discharge end, which recess is continuous and completely embraces the discharge opening. The inner side 7 of the recess 6 which lies remote to the discharge opening extends diagonally from the inner surface portion 8 of the tip 5 at an ob-

tuse angle materially exceeding 90 degrees, and the opposite side 9 of said recess adjacent the discharge end of said tip should meet the inner surface portion 10 thereof at an angle not exceeding 90 degrees, and preferably this angle 5 should be substantially less than 90 degrees, as illustrated.

The auxiliary tip or attachment 5 is preferably formed of a resilient insulating material, such as a synthetic rubber composition of the character, 10 for example, of "Duprene", which has all of the attributes of rubber but is unaffected by contact with solvents; other compositions or materials may, however, be employed. The tip or attachment 5 is, as shown in the drawing, arranged to 15 fit snugly over the discharge end of the tubular nozzle 4, and an annular surface or shoulder 11 is formed internally of said tip for engagement by the discharge end edge of said nozzle. The width of the annular surface or shoulder 11 is substantially equal to the thickness of the walls of the nozzle 4, so that the inner surface of the latter and the inner surface portion 8 of the tip 5 reside in substantially the same plane.

It is desirable that the tip or attachment 5 be 25 secured to the tubular nozzle 4 by means of a suitable adhesive, such as shellac, glue or the like, and for the purpose of protecting said tip 5 against damage and wear, a sleeve or the like 12 is preferably secured in a similar manner on the 30 outer surface of the tip. As shown in Fig. 2 of the drawing, the inner end portion of the sleeve 12 is curved inwardly, as indicated at 13, so that the edge thereof engages or contacts the adjacent outer surface of the nozzle 4 to effectively ground through the latter any static electricity that may have been generated in the receptacle or tank being filled from said nozzle, and the outer end portion of said sleeve 12 is 35 preferably curved a slight distance outwardly, 40 as indicated at 14, to conform to the curvature of the underlying surface of the tip or attachment 5, so that any tendency for the outer edge of the sleeve to cut into or damage said tip is substantially eliminated.

45 By forming the tip or attachment 5 of resilient material, such as a synthetic rubber composition of the character, for example, of "Duprene", distinctly novel buffering characteristics are afforded 50 said attachment, which effectively eliminates the possibility of damaging, scratching or otherwise marring the painted or enameled surfaces surrounding the inlet opening to the tank or receptacle being filled from the liquid-supply nozzle.

Furthermore, by providing a tip or attachment of the character described with a recess 6 constructed and arranged in the foregoing manner, I have found that there is a distinct tendency for the gasoline or other liquid entering the recess to become impounded and retained therein, this tendency being evidenced by the fact that the upper level of the liquid in the lower portion of said recess 6 will assume a position, as indicated at 15 in Fig. 2, actually above the horizontal level of the outer edge of the recess. Also by forming the inner side 7 of the recess 6 at the aforesaid angle or inclination with respect to the inner surface portion 8 of the tip or attachment 5 and the inner surface of the tubular nozzle 4, I reduce the tendency of the liquid gravitating down the inner surface of the latter to drop freely from the outer edge of said surface portion 8 and cause said liquid instead to flow smoothly into said retaining recess 6, and it is especially desirable that the juncture between the outer side 9 of the recess and the surface portion 10 of the attachment 5 shall provide a sharply angular formation, as this tends to resist the flow of liquid from said recess and materially increases the liquid-retaining capacity thereof.

While a specific embodiment of my tip or attachment has been set forth herein for purposes of description, it is not intended that the invention shall be precisely limited to said embodiment, but that changes and modifications may be incorporated in the construction and composition thereof within the scope of the annexed claims.

I claim:

1. The combination including a tubular liquid supply nozzle, an anti-drip member secured to the discharge end thereof, said member having its inner surface interrupted by a liquid-retaining recess the side of which adjoining the discharge end thereof forms with said inner surface an angle not in excess of 90 degrees and the opposite side an angle in excess of 90 degrees with the

inner surface, and a protective sleeve secured to the outer surface of the member.

2. The combination including a tubular liquid supply nozzle, a member secured to the discharge end of said nozzle, said member having a liquid-retaining recess located internally thereof adjacent the discharge end of the nozzle, and a protective sleeve secured to the outer surface of the member, said sleeve being of non-insulating material and contacting said nozzle for the purpose of grounding static electricity to the latter.

3. The combination including a tubular liquid supply nozzle, a member secured to the discharge end of said nozzle having its inner surface interrupted by a liquid-retaining recess, said member being composed of resilient material and operable as a buffer to prevent damage to surfaces with which the same may contact, and a protective sleeve secured to the outer surface of the member.

4. The combination including a tubular liquid supply nozzle, a member secured to the discharge end of said nozzle having its inner surface interrupted by a liquid-retaining recess, said member being composed of resilient material and operable as a buffer to prevent damage to surfaces with which the same may contact, and a protective sleeve secured to the outer surface of the member, said sleeve being of non-insulating material and contacting the surface of said tubular nozzle for the purpose of grounding static electricity to the latter.

5. The combination including a tubular liquid supply nozzle, a member of resilient material secured to the discharge end of said nozzle and having its inner surface interrupted by a liquid-retaining recess, said member being in the form of a sleeve embracing said supply nozzle and terminating in an enlarged head containing said recess, said head being located beyond the terminal end of said supply nozzle, and an outer protective sleeve closely embracing the inner end of the sleeve first named.

WILLIAM P. CAMERON.
